UNITED STATES PATENT OFFICE.

JOHN CANELLES, OF SUPERIOR, WISCONSIN.

WRENCH.

1,387,761.

Specification of Letters Patent. Patented Aug. 16, 1921.

Application filed December 2, 1920. Serial No. 427,830.

To all whom it may concern:

Be it known that I, JOHN CANELLES, a citizen of the United States, residing at Superior, in the county of Douglas and State of Wisconsin, have invented certain new and useful Improvements in Wrenches, of which the following is a specification.

This invention relates to improvements in wrenches.

10 An important object of the invention is the provision of a wrench embodying stationary and movable jaws, in which the various elements associated therewith for operation, are detachably connected together 15 to form a compact and efficient tool.

A further object of the invention is the provision of a wrench of the above character, which is provided with a plurality of rigid and movable jaws, to grip both plane 20 and curved surfaces.

25 A further object of the invention is the provision of a wrench of the above described character having embodied therein a wire cutting device, a nail extracting element; and a hammer adapting the tool for a combination of purposes, as a utility device.

Other objects of the invention will appear during the course of the following detailed description.

30 In the accompanying drawings forming a part of this specification, and in which like reference characters designate like parts throughout the same:

Figure 1 is a side elevation of the improved wrench.

Fig. 2 is an end elevation of the improved wrench.

Fig. 3 is a fragmentary cross sectional view showing the wrench construction.

40 Fig. 4 is an end elevation showing the stationary frame of the improved wrench.

Fig. 5 is a cross section taken on the line 5—5 of Fig. 1.

Fig. 6 is a plan view showing the jaw construction of the movable frame.

Fig. 7 is a fragmentary cross sectional view showing a detail of the invention.

In the drawings, wherein for the purpose of illustration is shown a preferred embodiment of the invention, the letter A designates the stationary frame, having a movable frame B associated therewith, and an advancing sleeve or handle C being employed for the purpose of moving the movable frame longitudinally with respect to 55 the stationary frame.

The stationary frame A is provided with a jaw 10 projecting laterally therefrom, which jaw is substantially circular in cross section, however, being provided with the 60 flat face 11 as an article engaging surface. The jaw 10 is uniform in cross section throughout, and is provided with a hammer surface 12 upon the end thereof. The stationary frame A is provided with a second 65 jaw 13, projecting laterally from the frame, and in a direction opposite to that of the jaw 10. The jaw 13, is of different formation than jaw 10, having a concave article engaging surface 14, which is preferably provided 70 with the serrations 15 in the form of teeth. The jaw 13 gradually diminishes toward its free end to provide the nail extracting crevice 16 thereon. The stationary frame A is provided upon each side of the longitudinal axis of the jaws 10 and 13 with a depending guide leg 17, integral with the structure of the jaws, to provide the open or recessed portion 18 intermediate the guide legs 17. The guide legs 17 are of the same 75 length, one of them being provided with a screw threaded opening 19 near its free end, while the other guide leg is provided with the counter-sunk opening 20 therein, the openings 19 and 20 having a common axis. 80 Intermediate the free ends of the legs 17 and their connection with the jaw structure of the frame A, they are provided upon the exterior surface with the shoulders 21, the same being formed by a reduction in the 85 cross section of the metal from that point to the free end of each of the guide legs 17.

The movable frame B comprises a jaw 25 adapted to co-act with the jaw 10 of the stationary frame A and which is provided 95 with the flat article engaging surface 26, adapted to abut the surface 11 of the jaw 10, when the movable jaw and stationary jaw are in closed relation. It is preferred that the jaw 25 terminates short of the end 100

12 of the jaw 10 to allow freedom of movement for the jaw 10 when using the same as a hammer. The movable frame is likewise provided with a jaw 27 opposite to the 5 jaw 25 and in the same longitudinal axis therewith, which is provided to co-act with the jaw 13 of the stationary frame A. The jaw 27 terminates short of the nail extracting crevice 16 of the jaw 13 to give a better 10 leverage to the tool, when using the jaw 13 as a nail extractor. The jaw 27 is provided with a concaved surface 30, having the serrated teeth 31 thereon, and which concaved article engaging surface 30 is adapted to co- 15 act with the article engaging surface 14, of the jaw 13, to grip articles which are circular, or which present smooth surfaces not so readily adapted to be engaged intermediate the jaws 10 and 25. A shank 34 is provided, 20 integral with the jaws 25 and 27, the same being externally screw threaded. In order to provide an operating structure, the movable jaw B is provided with opposite grooves or recesses 36, which extend longitudinally of the axis of the shank 34, a groove 36 intersecting the screw threads and jaws of the movable frame E, upon each side of the longitudinal axis of the jaws 25 and 27.

30 The screw threaded shank 34 is thus distinctly divided into two screw threaded sections or portions 37 and 38.

The movable jaw B is slidably connected to the stationary jaw A by having the guide legs 17 of the stationary jaw A disposed within the grooves 36 of the movable jaw B, thus sliding mounting the movable jaw without chance of rotation of one with respect to the other.

40 In order to prevent disconnection of the movable jaw B from the stationary jaw A, a pivoted member 40 is provided, having the enlarged head 41 thereon, which is substantially the same width as the recess 18 45 between the guide legs 17; and a depending shank 42, having the screw threads 43 upon the lower end thereof. The pivoted member 40 is provided with an opening in the head 41 adapted for receiving a screw 45, which 50 screw is adapted to be extended in the openings 19 and 20 of the legs 17 for the purpose of pivoting the member 40 to the lower ends of the legs 17, to prevent disconnection of the movable frame B from the frame A.

55 The advancing sleeve C is internally screw threaded for engaging with the screw threaded portions 37 and 38 of the shank 34, the exterior surface 46 being preferably circular, and having the knurled portions 47 thereon as a better gripping means, for operation of the device. The sleeve C gradually diminishes toward its end and is provided with an aperture 49 therein adapted to receive the shank 42 of the member 40 60 therethrough, in such manner that the screw

threaded portion 43 of the member 40 projects from the bottom 50 of the sleeve C. A seat 51 is provided adjacent the opening 49 having mounted thereon the washer 52, for abutting beneath the head 41 of the pivoted member 40, to prevent any further upward movement of the sleeve C upon the stationary frame A. The upper end 55 of the sleeve C likewise abuts against the shoulders 21 of the guide legs 17 to similarly prevent upward movement of the sleeve C upon the movable frame A. 75

To prevent disconnection of the sleeve C from the wrench, the crown nut 55^a is adjusted upon the screw threaded portion 43 80 of the member 40 and abutting the surface 50 of the sleeve C for the purpose of maintaining the advancing sleeve C tightly and firmly in relation to the frame A, preventing longitudinal movement of the sleeve C 85 while permitting its rotation with respect to the frame A.

The screw threaded portion of the shank 34 is provided with left handed screw threads and upon assemblage of the advancing sleeve 90 C to engage the screw threaded portions 37 and 38 of the shank 34, and upon rotation of the movable advancing sleeve C to the right, the internal screw threads of the advancing sleeve C will force the movable frame B upward, due to engagement with the screw threads of the shank 34. Thus the jaws 26 and 27 of the movable jaw B can be advanced into operative engagement with the jaws 10 and 13 of the stationary frame A. 100 In order to allow contact of the jaws 25 and 10, the movable frame B is provided with the recess 56, adapted to receive a portion 57 of the frame A adjacent the connection of the guide legs 17 with the stationary frame. 105 In order to allow considerable expansion of the jaws, the shank 34 is recessed upwardly from the free end thereof as shown at 58, the surface 59 of the shank, adapted to abut the head 41 of the member 40, when the movable frame B is disposed in its most open position with respect to the stationary frame A.

110 A wire cutting device is embodied in the structure, namely, by the upwardly extending projection 60 provided upon the jaw 25, which extends to one side of the longitudinal center of the jaw 25 and is provided with the cutting edge 61. The jaw 10 is provided with a coacting and depending projection 62 extending upon the opposite side of the center line of the jaw, from that of the projection 60 and provided with the cutting edge 63 adapted to co-act with the cutting edge 61 of the projection 60 to cut a 115 wire or similar article, when the same is inserted to be engaged by the cutting edges, and upon operation of the device to advance the jaws 10 and 25 into proximity with each other. A recess 64 is provided in the jaw 120 125 130

10 which is adapted to receive the projection 60 and a similar recess 65 is provided in the jaw 25 adapted to receive the projection 62 upon the jaw 10; the recesses 64 and 65 being 5 provided in order that the surfaces 11 and 26 of the jaws 10 and 25 respectively, may be brought into abutting relation.

The hammer surface 12 of the jaw 10 could be used as an anvil when horizontally disposed, upon engagement of the jaws 27 and 10 13, with some object.

It is to be understood that the form of my invention herewith shown and described, is to be taken as a preferred example of the 15 same, and that various changes in the shape, size and arrangement of parts may be resorted to without departing from the spirit of the invention or the scope of the subjoined claims.

20 I claim:

1. In a wrench, the combination of a stationary frame including a jaw and depending shank, a movable frame including a jaw, and an externally screw threaded shank, said movable frame-shank having a recess therein for reciprocation over the shank of said stationary frame, an internally screw threaded rotative sleeve engaging the shank of said stationary frame, to 25 prevent relative longitudinal movement of said last mentioned shank and sleeve, the screw threads of said rotative sleeve being in engagement with the screw threads on the shank of said movable frame for advancing 30 said movable jaw upon rotation of said sleeve.

2. In a wrench, the combination of a stationary frame including a wrench jaw, and a pair of spaced guide legs, a movable frame 40 including a wrench jaw, and a screw threaded shank for engagement intermediate the guide legs; detachable means for holding the free ends of said spaced legs together, and preventing disconnection of the movable 45 frame from the stationary frame, and an advancing sleeve for engagement with the screw threaded shank of the movable frame to advance the movable frame longitudinally with respect to the stationary frame.

50 3. In a wrench, the combination of a stationary frame including a wrench jaw and a pair of spaced guide legs; a movable frame, including a wrench jaw, and a screw threaded shank for engagement intermediate the 55 guide legs; detachable means for preventing disconnection of the movable frame from the stationary frame; and an advancing sleeve for engagement with the screw threaded shank of the movable frame to advance the 60 movable frame longitudinally with respect to the stationary frame.

4. In a wrench, the combination of a stationary frame including a jaw, and spaced depending legs; a movable frame including a 65 jaw, and a depending screw threaded shank,

said shank having recesses therein for reciprocation of said depending legs, a rotative screw threaded sleeve in operating engagement with the screw threaded shank, and means engaging the rotative sleeve and depending legs for permitting longitudinally feeding of the movable frame with respect to the stationary frame, and preventing relative longitudinal movement of said sleeve upon said stationary frame, upon rotation of 75 said sleeve.

5. In a wrench, the combination, of a stationary frame including a wrench jaw, and depending spaced guide legs; a movable frame including a wrench jaw, and a screw 80 threaded shank, said threaded shank having longitudinal recesses therein to receive the guide legs of the stationary frame; detachable means pivotally connected to the free ends of the guide legs to prevent disconnection of the stationary and movable frame; and an advancing sleeve adapted for rotative engagement with the stationary frame, and movable frame, to advance the movable frame longitudinally with respect to the stationary frame.

6. In a wrench, the combination, of a stationary frame, including a wrench jaw, and guide legs; a movable frame including a wrench jaw for co-acting with the wrench 95 jaw of the stationary frame, and a screw threaded shank, said screw threaded shank having longitudinal recesses thereon for receiving the guide legs of the stationary frame, a detachable member pivoted to the 100 guide legs and having a head integral therewith for receiving an end of the movable frame shank to prevent disconnection of the movable frame from the stationary frame, a sleeve being internally screw threaded for 105 engagement with the screw threads of the movable frame, for advancing the movable frame with respect to the stationary frame; the lower end of the sleeve being open for projecting of the detachable pivoted member, and means in engagement with the pivoted member for preventing disconnection of the advancing sleeve.

7. In a wrench, the combination, of a stationary frame including a wrench jaw, and 115 guide legs integral therewith, having shoulders intermediate the ends thereof; a movable frame including a wrench jaw, and a screw threaded shank, said shank and wrench jaw having recesses therein to slidably receive the guide legs of the stationary frame; a detachable member pivotally connected to the free ends of the guide legs, including a head for engagement with the movable frame 120 to prevent disconnection of the same from the stationary frame, and a screw threaded shank on said detachable member extending below the ends of the guide legs; an advancing sleeve being internally screw threaded for engagement with the screw threads of the 125 130

movable frame shank, and having an aperture in the bottom for projection of the screw threaded shank of the detachable member; a nut upon said screw threaded shank of the detachable member and adapted to engage the sleeve to prevent disconnection thereof from the wrench, said advancing

sleeve adapted to engage the shoulders of the guide legs to prevent longitudinal movement of the advancing sleeve with respect to the stationary frame, upon rotation thereof to longitudinally advance the movable frame with respect to the stationary frame.

JOHN CANELLES.
